(57) **CLAIM**

The ornamental design for a doll stand with base, as shown and described.

DESCRIPTION

FIG. 1 is a perspective view of a first design of a doll stand with base;

FIG. 2 is front view of a second design of the doll stand without the base;

FIG. 3 is a rear view thereof;

FIG. 4 is a side view thereof;

FIG. 5 is a side view thereof;

FIG. 6 is a top view thereof;

FIG. 7 is a bottom view thereof; and,

FIG. 8 is an exploded view thereof.

The broken line showing of the doll stand with base is for the purpose of illustrating portions of the article that form no part of the claimed design.
